[57] **CLAIM**

The ornamental design for a temperature limiting cap for containers, as shown and described.

DESCRIPTION

FIG. 1 is a front perspective view of a temperature limiting cap for containers showing my new design;

FIG. 2 is a top plan view thereof;

FIG. 3 is an end view thereof;

FIG. 4 is an opposite end view thereof;

FIG. 5 is one side view thereof, the opposite side view being a mirror image thereof; and,

FIG. 6 is a bottom plan view thereof.
